UNITED STATES PATENT OFFICE

WALTER F. ROGERS, OF CICERO, ILLINOIS, ASSIGNOR TO CROWN STOVE WORKS, OF CICERO, ILLINOIS, A CORPORATION OF ILLINOIS

DESIGN FOR A STOVE

Application filed November 20, 1931. Serial No. 41,792. Term of patent 14 years.

To all whom it may concern:

Be it known that I, WALTER F. ROGERS, a citizen of the United States, residing at Cicero, in the county of Cook and State of Illinois, have invented a new, original, and ornamental Design for Stoves, of which the following is a specification, reference being had to the accompanying drawings, forming part thereof, in which—

Fig. 1 is a perspective view of a gas stove showing my new design.

Fig. 2 is a similar view but showing the hinged cover and the front guard in open positions.

I claim:

The ornamental design for a stove or similar article, as shown.

WALTER F. ROGERS.
